UNITED STATES PATENT OFFICE

2,309,489

ELECTRIC CIRCUIT INTERRUPTING DEVICE

Edwin A. Williams, Jr., Lansdowne, and Carl L. Schnuck, Philadelphia, Pa., assignors to General Electric Company, a corporation of New York

Application August 2, 1940, Serial No. 349,847

10 Claims. (Cl. 200—120)

The present invention relates to high voltage circuit interrupters of the kind referred to as current limiting devices because of their ability under severe short-circuit conditions, to limit the short-circuit current to a peak magnitude considerably below that of the prospective or available current which otherwise would be produced.

There have been developed devices of this character wherein the current interrupting link or agency includes a long fusible conductive section surrounded by an inert refractory material of high dielectric strength, the form, composition and arrangement of which material and conductive section are such that, upon dissipation of the conductive section by severe short-circuit current, there is inserted into the current path a high resistance which sharply limits the current rise and produces a rapid current decay, resulting in final circuit interruption in an extremely short period of time, not exceeding a half cycle in the case of alternating current. The sudden increase in resistance of the arc path gives rise to transient voltage surges, the magnitude of which depends upon the current at the instant that the resistance is inserted, as well as upon the magnitude and rate of insertion of the resistance. It is not possible altogether to eliminate such voltage surges, particularly with current limiting devices of high current interrupting capacity, because of the necessity for rapid insertion of high resistance in order to produce the desired current limiting action and rapid circuit interruption. With some previous designs of current limiting devices and under some conditions of circuit interruption, however, it has been found that the surge voltages may reach undesirably high peak magnitudes which might endanger the insulation of connected apparatus.

It is an object of the present invention to provide a current limiting circuit interrupting device having an interrupting link or agency of improved construction which makes it possible to secure the desired sharp current limitation and rapid interruption of a severe over-current or short-circuit condition, and which at the same time is capable of controlling the insertion of the current limiting and interrupting resistance so as to insure against the danger of occurrence of surge voltage peaks in excess of predetermined limits.

In general, an interrupting link or agency constructed in accordance with the present invention, embodies a plurality of elements in parallel

relationship and so arranged that they function successively in a manner to cause insertion of resistance in such amounts and at such rates that there is not produced at any time during the interrupting process, a rate of current decay which will cause a surge voltage peak in excess of a predetermined magnitude.

A more complete understanding of the details of that which we consider to be novel and our present invention will be secured from the following description and the appended claims, taken in conjunction with the accompanying drawings wherein

Fig. 1 shows, in longitudinal cross-section, an exemplary form of current limiting circuit interrupting device to which the present invention is applicable;

Figs. 2, 3, 4, and 5 show details of construction of different forms of current interrupting links which embody the present invention and which are suitable for employment in a device such as that shown in Fig. 1;

Fig. 6 is an enlarged perspective view of a part employed in the constructions of Figs. 1, 2, 3, and 4;

Fig. 7 is a longitudinal section of one end of a device such as shown in Fig. 1, illustrating the manner of incorporating therein an interrupting link having elements constructed as shown in Figs. 4 and 5;

Fig. 8 is an end view of the core employed in the structures shown in Figs. 1 and 7;

Fig. 9, for purposes of later description and comparison, contains diagrammatic representations of oscillographic curves of current and voltage, respectively, illustrating conditions of circuit interruption as secured with a current limiting device wherein the current interrupting link is of a form old in the art; and

Fig. 10 contains diagrammatic representations of oscillographic curves of current and voltage, respectively, illustrating conditions of circuit interruption as secured with an interrupting link constructed in accordance with the present invention.

By reference to the drawings, it will be seen that the illustrated circuit interrupting device has a tubular enclosing casing 20 upon the opposite ends of which are disposed metallic terminal ferrules 21. While the casing is indicated as being constructed of glass, other suitable materials of high dielectric strength, such as porcelain, may be employed if desired. The terminal ferrules are secured on the casing by any suitable form of metal-to-glass seal, indicated at

22, and the outer ends of the ferrules are closed by sealed-in caps 23. As is common practice in devices of the type illustrated, an insulating and refractory core 24, extending longitudinally in casing 20, is provided for the purpose of supporting the long current interrupting link so that the latter may be accommodated in a casing of practical dimensions. The particular interrupting link shown spirally wound on the core in Fig. 1 is of the form shown in Fig. 2 and includes two elements 25 and 26 in parallel relationship, which are described in detail hereinafter. Any of the other forms of interrupting links illustrated in the drawings, may be supported on the core in a similar manner. The interior of the casing 20 around the core is filled with a granular refractory arc-quenching material 27, such as sand or pulverized quartz, which has high dielectric strength and is substantially inert, or non-gas-producing, at the temperatures likely to be encountered during circuit interruption. As will be evident from Figs. 1 and 2, core 24 has a plurality of longitudinally extending fins or ribs 28 which engage the conductors of the interrupting link only at spaced points and serve to maintain the conductors spaced outwardly from the central body portion of the core. Thus, the maximum length of the conductors is embedded in and directly exposed to the arc-quenching material.

The opposite ends of elements 25 and 26 are secured to terminals 30 which are mounted respectively on opposite ends of core 24. Any suitable form of terminal may be employed for the purpose, but the particular terminals employed in the illustrated construction are of the improved form disclosed in application Serial No. 347,437, filed July 26, 1940, now Patent No. 2,294,132, granted August 25, 1942, in the name of C. L. Schuck, and assigned to the same assignee as the present invention. As fully explained in the said Schuck application, the terminals engage the fins of core 24 in a manner such as to prevent unwinding or slipping of the conductors of the interrupting link. As additional precaution against displacement of the terminals, wires 31 are wrapped around the ends of the core in a manner securely to anchor the terminals in place. Tabs 32 extend from the terminals and are joined to the inner surfaces of terminal ferrules 21 so as to provide electrical connections between the terminal ferrules and the opposite ends of the interrupting link.

As previously indicated, interrupting links constructed in accordance with the present invention, include a plurality of elements in parallel relationship and designed to function successively. For purposes of conveying a complete understanding of the fundamentals of the invention, our improved construction will be treated as incorporating two principal elements. One of these elements is designed to provide the main current carrying path under normal circuit conditions and to initiate the interrupting process under abnormal circuit conditions. This element will be designated as the "main element" or "current element." The other element, which will be designated the "auxiliary element" or "voltage element," is designed to take over the interrupting process initiated by the current element, and to control the insertion of resistance so as to prevent the production of surge voltage peaks in excess of a predetermined magnitude.

In the embodiment of Fig. 2, element 25 is the current element, and is comprised of a long fusible

conductor of thin cross-section, which may be of any suitable form and material in accordance with known principles for the construction of interrupting elements for current limiting circuit interrupting devices. The conductor 33 of the illustrated construction comprises a fine silver wire, which is particularly satisfactory for current conduction under normal circuit conditions. Smallbeads or thermal reservoirs 34, of refractory insulating material, surround short sections of wire 33, preferably adjacent the middle thereof, for the purpose of determining the minimum current at which interruption takes place. These thermal reservoirs prevent contact of the enclosed wire sections with the granular filler material and hold in the heat. Thus it is insured that the wire will melt on an overload involving a lower magnitude of current than would be possible with the same conductor without the thermal reservoirs.

The voltage element, designated 26 in the construction of Fig. 2, comprises two conductors 35 connected at their outer ends to terminals 30 and joined at their inner ends by an insulating refractory member 36. As will be seen best from Fig. 6, each of the conductors 35 is looped through a respective one of the openings 37 in member 36, and the conductors are secured by twisting, as indicated at 38. Member 36 maintains the ends of conductors 35 in spaced relationship so as to provide a gap which is calibrated to flash over at a predetermined voltage. The calibration of the gap is determined in a manner hereinafter pointed out and may vary for interrupting devices of different voltage and current ratings. The gap may be located at the end of a voltage element having one long conductor instead of two serially related shorter conductors. However, it has been found that best results are obtained with the gap located adjacent the middle of the voltage element as illustrated. The form and dimensions of conductors 35 are determined in accordance with known principles for the construction of fusible elements for current limiting circuit interrupting devices, with certain variations which will be pointed out. In accordance with the present invention, conductors 35 are comprised of a material having high electric resistivity and a high temperature coefficient of resistance. We have found that a good material for the purpose is a nickel-chromium-iron alloy known by the trade name "Hytemco," although other suitable materials having the above mentioned characteristics may be employed if desired.

The current element embodied in interrupting links constructed in accordance with the present invention, may comprise either a single unit, such as that designated 25 in Fig. 2, or a plurality of similar units connected so as to provide parallel branches as shown in Fig. 5. Although the individual units are designated by the numeral 40 in Fig. 5, they are fundamentally the same in construction as the unit designated 25 in Fig. 2. Likewise, the voltage element may comprise either a single unit, such as that designated 26 in Fig. 2, or may comprise a plurality of similar units connected in parallel branches as shown in Fig. 4, the individual units 41 of Fig. 4 being of the same fundamental construction as the unit 26 of Fig. 2. The number of units or branches incorporated in the current element or the voltage element depends upon the current rating of the particular interrupting device in which the elements are employed. It has been found that most effective current limiting and circuit in-

rupting action is produced with fusible conductors of thin cross-section. Hence, when the current rating demands a relatively large total cross-section, it is preferable to divide this total cross-section into a number of parallel units in which the individual conductors are of such cross-section as to provide the most effective current limiting and circuit interrupting action. If, in the practice of the present invention, it is found that the total number of units in the current and voltage elements is greater than can be conveniently connected between a single set of terminals, such as those previously designated 30, then the units of the current element may be connected between one set of terminals and the units of the voltage element connected between a separate set of terminals. For clarity, the terminals in the construction of Fig. 5 are designated 42, while the terminals in the construction of Fig. 4 are designated 43, although both sets of terminals may be of the same form as those designated 30. In case constructions such as those shown in Figs. 4 and 5 are employed, the current and voltage elements, when installed in the interrupting device, are arranged in parallel spirals in a manner such as indicated in Fig. 7.

The current elements of Figs. 2 or 5, if employed without the voltage elements, would correspond fundamentally to the interrupting elements of previously known forms of current limiting circuit interrupting devices. In order more clearly to show the advantages of employing our auxiliary or voltage element, the operation under severe short-circuit conditions of an interrupting device employing an interrupting element corresponding to the current element alone, now will be described. This operation is best explained by reference to Fig. 9, wherein are represented oscillograph curves of short-circuit interruption by means of a current limiting circuit interrupting device employing an interrupting element similar to the current element of Fig. 2, it being pointed out, however, that substantially the same character of interruption would be secured if a plural-unit element, corresponding to the current element of Fig. 5, were employed. The short-circuit, and over-heating of the conductor, such as 33, begin at a. Substantially simultaneous dissipation of all portions of the effective fusible length of the conductor, and initiation of arcing, take place at b. When the conductor volatilizes at b the metallic vapors are dispersed extremely rapidly through the spaces between the relatively cool granules of the surrounding quenching material and condense on the surfaces of the granules, so that the vapors no longer are available for current conduction. Also, the intimate physical contact between the hot arc and the cool granules causes an exceedingly rapid transfer of heat from the arc to the quenching material. Most of the arc energy is dissipated in this heat transfer and the pressure generated in the interrupting device is practically negligible. The substantially simultaneous volatilization of all portions of the length of the fusible conductor, the sudden removal of the metallic vapors from the arc path, and the extremely rapid cooling of the arc, have the effect of suddenly inserting an extremely high resistance into the current path, which sharply limits the current substantially to the value required to melt and volatilize the conductor. The broken lines indicate the manner in which the prospective or available current would develop under severe short-

circuit conditions if the interrupting device were not connected in the circuit. It has been found that by means of the action described, a prospective short-circuit current of say 60,000 rms. amperes may be limited to a maximum peak value of between 200 and 20,000 amperes, depending upon the particular design of the interrupting device and the particular circuit conditions.

10 The rapid insertion of high resistance also causes a very rapid current decay from b to some point generally designated c in Fig. 9, after which the current decays somewhat less precipitously and is finally interrupted at d, which corresponds to the zero point of the normal circuit voltage. The final interruption of the current is accomplished with minimum disturbance, and takes place within an extremely short period of time which does not exceed a half cycle in the case of alternating current interruption, as illustrated in the drawings. The described current limiting action is produced under all conditions within the rating of the interrupting device, provided the magnitude of current required to melt and volatilize the fusible conductor is reached before attainment of the peak magnitude of prospective current. Obviously, current limiting action cannot be produced if the peak magnitude of prospective current is reached before attainment of the magnitude of current required to melt and volatilize the conductor.

15 The sharp limitation of the current rise and the subsequent precipitous current decay produced by the sudden insertion of high resistance as previously described, gives rise to a voltage surge which is initiated approximately at the instant of volatilization of the fusible conductor. The peak magnitude of the surge voltage, indicated at e, depends upon the ohmic value of the resistance inserted, the value of the current at the instant of melting, and the rate of current decay, as well as upon the constants of the circuit. With certain forms of current limiting interrupting devices and under some conditions, the surge voltage may rise to a crest magnitude which is undesirably high and which may be above the established impulse insulation levels of connected apparatus.

20 The employment of an auxiliary voltage element in accordance with the present invention, effectively prevents such undesirably high peak magnitudes of surge voltage. The operation of an interrupting device employing our improved form of interrupting link, is best described by reference to Fig. 10. This operation is substantially the same with either a single-unit form of voltage element, such as that designated 26 in Fig. 2, or a voltage element employing a plurality of parallel connected units or branches such as those designated 41 in Fig. 4. Hence the operation will be described as if the single-unit construction of Fig. 2 were employed. It is believed well to point out here that of necessity the element of time is exaggerated in the subsequent description of operation and in the curves shown on the drawings. In reality, the described stages of the interrupting process take place in periods of a few microseconds.

25 By reference to Fig. 10, it will be seen that the initial stage of the interrupting process is substantially the same as that previously described in connection with Fig. 9, since during this initial stage only the current element functions, the voltage element being prevented from carrying

current by reason of the gap provided by member 36. The short-circuit and abnormal heating of the current element commence at *a*. The high resistance suddenly inserted into the current path upon dissipation of the current element, sharply arrests the current rise at *b* and causes a rapid current decay. As previously indicated, the peak current value indicated at *b*, corresponds substantially to the current required to melt the current element and is considerably below the prospective or available current peak. The rapid current decay immediately following dissipation of the current element gives rise to a voltage surge as indicated at *f* in Fig. 10. The voltage element takes no part in this initial stage of the interrupting process but is conserved, by the gap between the ends of conductors 35, for most effective operation during later stages in the interrupting process. The calibration of the gap in the voltage element determines the magnitude to which the voltage may rise across the terminals of the interrupting device. Thus, by proper calibration of the gap, the voltage surge *f* may be limited to a peak magnitude considerably below that, indicated at *e* in Fig. 9, which would be produced if the current element alone were employed. In practice, for any particular interrupting device the gap is calibrated so as to prevent the first voltage surge *f* from attaining a peak magnitude in excess of the limit, or impulse insulation level, which is predetermined in accordance with the application for which the interrupting device is designed.

When the predetermined magnitude of voltage is reached and the gap breaks down, conductors 35 of the voltage element are brought into the circuit in shunt relationship to the arc path formerly occupied by the current element. This occurs at a point such as that indicated at *g* on the current curve in the upper part of Fig. 10. The current decay immediately subsequent to connection of conductors 35 in circuit is less rapid than that represented by the portion *b*-*g* on the current curve of Fig. 10, since the resistance offered by conductors 35, though high, is less than that of the arc path formerly occupied by the current element. As conductors 35 heat up, their resistance rapidly increases so that a further current reduction is produced as indicated by the portion of the current curve *g*-*h*. Conductors 35 finally attain their melting temperature and volatilize at *h*, whereupon the resistance rises at a rapid rate and produces a rapid current decay, such as indicated from *h* to *i*, and final interruption of the current at *d*. The rapid decay of current subsequent to volatilization of the voltage element produces a voltage surge as indicated at *k* on the voltage curve in the lower part of Fig. 10. However, during the interval between volatilization of the current element and volatilization of the voltage element, a considerable portion of the system energy has been dissipated, and the current has reached a reduced rate of decay and a reduced value, indicated at *h*, to which the surge produced upon volatilization of the voltage element is roughly proportional. Thus, the peak magnitude of the second voltage surge *k* is not as great as that, indicated at *e* in Fig. 9, which would be produced if the current element alone were employed.

We have found that the interval between melting of the current element and melting of the voltage element is a very important factor in determining the magnitude of the voltage surge crest. If this interval is too short, the second

voltage surge will be superimposed upon the first voltage surge peak, resulting in a high surge crest. The time spacing between melting of the current and voltage elements therefore should be such that the second voltage surge is not initiated at or near the peak of the first voltage surge, but rather is initiated after the first voltage surge has fallen to a value approaching the normal circuit voltage. The interval between melting of the current element and melting of the voltage element usually should be at least 100 to 150 microseconds. The magnitude of the second voltage surge is determined to a large extent by the delay afforded before melting of the voltage element. Within practical limits, the greater the interval between melting of the current and voltage elements, the smaller will be the peak magnitude of the second voltage surge. This interval can be controlled by proper calibration of the gap of the voltage element and the melting characteristics of the voltage element. Increasing the length of the gap will delay subjection of the voltage element to the short-circuit current, and thus will delay initiation of heating of the conductive portions of the voltage elements. However, as previously indicated, the calibration of the gap determines the peak of the first voltage surge, so that a limit is reached beyond which it is not desirable to increase the gap spacing. With the gap spacing determined, and with all other conditions remaining the same, variation in the magnitude of the second voltage peak may be secured by variation in the melting characteristics of the conductive portions of the voltage element. This can be accomplished by employing different resistance materials. Thus, if a voltage element comprised of a given resistance material does not afford a delay sufficient to prevent rise of the second voltage surge beyond a predetermined desired limit, there may be employed a voltage element comprised of a different resistance material having such melting characteristics as to provide the required delay. However, the melting characteristics of materials having suitable resistance characteristics, comparable to those of the nickel-chromium-iron alloy "Hytemco" previously mentioned, may not afford sufficient latitude under some conditions. Also, from a practical standpoint it is desirable to be able to employ a single material, having the proper resistance characteristics, for the voltage elements of a line of interrupting devices of different current and voltage ratings. Therefore, we prefer to employ a single resistance material of the proper characteristics, and to secure the desired delay in melting of the voltage elements by proper determination of their cross-section. Cross-section is used in the sense of total cross-section, of either the single-unit voltage element construction of Fig. 2 or a plural-unit voltage element construction such as shown in Fig. 4. If, for a given interrupting device, a voltage element of a given cross-section does not produce reduction in the surge voltage crest below the limit predetermined for the application for which the interrupting device is designed, then a voltage element of sufficiently larger cross-section may be employed to give the desired reduction.

The required ratio of cross-section of voltage element to cross-section of current element varies for different current and voltage ratings, the higher ratios being employed for the higher current ratings. We have found that ratios of cross-section of voltage element to cross-section of

current element falling somewhere in the range of about 1 to 4, depending upon the rating of the particular interrupting device, usually are sufficient to prevent surge voltages in excess of prevailing impulse insulation levels determined for the classes of apparatus with which these current limiting circuit interrupting devices are likely to be employed. It is not feasible to set forth herein specific exemplary dimensions and cross-section ratios for the current and voltage elements, since these vary considerably with different ratings and also depend upon particular impulse insulation levels. However, with an understanding of the fundamental teachings set forth herein and of known principles for the design of interrupting devices, such as described herein, one skilled in the art may readily determine by calculations or tests the dimensions and other details of design required for proper construction of an interrupting device in accordance with the present invention.

As previously indicated, the fundamental constructions hereinbefore described may be modified, so as to secure various operational characteristics for various applications. For example, the serially related conductors of the voltage element may be comprised of different materials, at least one of which has high electric resistivity, in accordance with the teachings set forth in the previously identified Schuck application. This would have the effect of causing the voltage element to operate in two stages so as to produce an even more gradual insertion of resistance. Also, the serially related conductors of the voltage element may be made of the same resistance material but of different cross-section so as to cause operation of the voltage element in two stages in accordance with the teachings of United States Patent No. 2,187,037 issued May 8, 1939, in the name of E. A. Lohrzen and assigned to the same assignee as the present invention. Such a construction is illustrated in Fig. 3 wherein the conductor 45 of the voltage element is of larger cross-section than the conductor 38. It is possible also to secure a plural-stage operation of a plural-unit voltage element, such as shown in Fig. 4, by providing gaps of different spacing in the different branches of the voltage element.

From the foregoing, it will be seen that our invention provides an improved way in which the advantages of a current limiting circuit interrupting device may be secured without the danger of production of voltage surges of undesirable peak magnitude. We therefore do not desire to be limited by the details of the constructions shown in the drawings, and intend to cover by the appended claims such modifications and other embodiments as employ the fundamentals of the invention hereinbefore fully described.

What we claim as new and desire to secure by Letters Patent of the United States is:

1. In an electric circuit interrupter of the current limiting type, a pair of terminals, means providing a circuit of good conductivity between said terminals and including a fusible section, means providing a second circuit between said terminals in parallel with said first circuit and including a high resistance conductive portion having a fusible section, gap means in series with said conductive portion of the second circuit to prevent the latter from carrying current until the voltage across the gap means reaches a predetermined magnitude following rupture of the fusible section of said first circuit, and arc-quenching means associated with said fusible sec-

- tions and capable of producing a current limiting action upon dissipation of each of said fusible sections under severe overcurrent conditions, said gap means and conductive portion of said second circuit controlling the insertion of resistance into the current path upon dissipation of the fusible section of said first circuit, so as to limit the surge voltage to a crest magnitude substantially lower than that which would be produced under the same conditions if said first circuit were employed without said gap means and second circuit.
2. In an electric circuit interrupter of the current limiting type, a pair of terminals, an element of good electric conductivity connected between said terminals and having a fusible section, a second element connected between said terminals in parallel with said first element and including a fusible conductive section having high resistance and a high positive temperature coefficient of resistivity, gap means in series with said fusible section of said second element to prevent current conduction by the latter until the voltage across the gap means reaches a predetermined magnitude following rupture of the fusible section of said first element, and arc-quenching means capable of producing a current limiting action upon dissipation of each of said fusible sections under severe overcurrent conditions, said gap means being arranged to break down at a voltage substantially lower than the peak magnitude of voltage surge likely to be produced upon severe overcurrent dissipation of the fusible section of said first element if the latter were employed without said second element and gap means, the fusible section of said second element being constructed so as to dissipate an appreciable time interval after break down of said gap means.
3. In an electric circuit interrupting device of the current limiting type, a casing having spaced terminals, granular inert refractory arc-quenching material of high dielectric strength enclosed in said casing, a circuit of good electric conductivity connected between said terminals and including a long fusible section embedded in said material, means providing a second circuit between said terminals in parallel with said first circuit and including a high resistance conductive portion having a long fusible section embedded in said material, and gap means in series with said conductive portion of said second circuit for preventing the latter from carrying current until the voltage across the gap means reaches a predetermined magnitude following rupture of the fusible section of said first circuit, said gap means and said conductive portion of said second circuit controlling the insertion of resistance into the current path upon dissipation of the fusible section of said first circuit so as to limit the voltage surges produced upon rupture of said fusible sections under severe overcurrent conditions to a crest magnitude substantially lower than the crest magnitude of voltage surge which would be produced under the same conditions upon dissipation of the fusible section of said first circuit if the latter were employed without said gap means and said second circuit.
4. In an electric circuit interrupter of the current limiting type, a pair of terminals, an element of good electric conductivity connected between said terminals and having a long fusible section, a second element connected between said terminals in parallel with said first element and including a long fusible conductive section hav-

ing high resistance and a high positive temperature coefficient of resistivity, gap means in series with the fusible section of said second element for preventing the latter from carrying current until the voltage across the gap means reaches a predetermined magnitude following rupture of the fusible section of said first element, and granular inert refractory arc-quenching material embedding the fusible sections of both of said elements, said gap means being arranged to break down upon being subjected to voltage of a magnitude which is substantially lower than the peak magnitude of voltage surge likely to be produced upon dissipation of the fusible section of said first element under severe overcurrent conditions if said first element were employed without said gap means and said second element, said fusible section of said second element being designed to fuse and dissipate an appreciable time interval after break down of said gap means.

5. In an electric circuit interrupter of the current limiting type, including spaced terminals, a current carrying element connected between said terminals and having a long fusible section, and a granular inert refractory arc-quenching material embedding said fusible section; a voltage control element connected between said terminals in parallel with said first mentioned element for limiting the crest magnitude of voltage surge produced upon interruption of severe overcurrent conditions, said control element including two serially related fusible conductive portions having a gap inserted therebetween for preventing current conduction by said conductive portions until the gap is subjected to voltage of predetermined magnitude following rupture of the fusible section of said first mentioned element, said conductive portions having high resistance and a high positive temperature coefficient of resistance, and granular inert refractory arc-quenching material embedding said conductive portions of the voltage control element.

6. In an electric circuit interrupter of the current limiting type, including spaced terminals, a current carrying element connected between said terminals and having a long fusible section, and a granular inert refractory arc-quenching material embedding said fusible section; a voltage control element connected between said terminals in parallel with said first mentioned element for limiting the crest magnitude of voltage surge produced upon interruption of severe overcurrent conditions, said control element including two serially related conductive portions, at least one of which conductive portions being designed to dissipate prior to dissipation of the other of the conductive portions upon subjection of said control element to excess current of large magnitude, at least said one conductive portion having high resistance, said control element also including means providing a gap in series with said conductive portions for preventing current conduction by the control element until the gap is subjected to voltage of predetermined magnitude following rupture of the fusible section of said first element, and granular inert refractory arc-quenching material embedding said fusible conductive portions of said control element.

7. In an electric circuit interrupter of the current-limiting type, a pair of terminals, means normally providing a first current path of good conductivity between said terminals and including a fusible section which is capable of reducing the current of the system associated with said circuit interrupter following a severe short circuit so rapidly as to tend to produce a harmful surge voltage on said system, and means providing in parallel with said first current path a second current path which carries substantially no current under normal conditions of said circuit interrupter, said last-mentioned means being so designed as to begin to carry the system current therethrough prior to the attainment of said harmful surge voltage on said system including resistance means varying in ohmic value in dependence upon the current passing therethrough and fusible so as finally to interrupt the current in said second path.

8. In an electric circuit interrupter capable of substantially limiting the magnitude of fault current flowing therethrough including a fusible element for normally providing a current path having good conductivity through said circuit interrupter, and means for limiting the transient voltage surge which results due to the current-limiting feature of said circuit interrupter under severe fault conditions to a predetermined safe value comprising a circuit connected in parallel with said fusible element which normally carries substantially no current but after fusion of said fusible element and before said voltage surge can exceed said predetermined safe value carries the fault current through said circuit interrupter, said last-mentioned means being fusible finally to interrupt the circuit at least 100 micro-seconds after the fusion of said fusible element.

9. In an electric circuit interrupter capable of substantially limiting the magnitude of fault current flowing therethrough including a fusible element for normally providing a current path having good conductivity through said circuit interrupter, and means for limiting the transient voltage surge which results due to the current-limiting feature of said circuit interrupter under severe fault conditions to a predetermined safe value comprising a circuit connected in parallel with said fusible element including a plurality of parallel gaps which normally carry substantially no current until after fusion of said fusible element.

10. In an electric circuit interrupter capable of substantially limiting the magnitude of fault current flowing therethrough including a fusible element for normally providing a current path having good conductivity through said circuit interrupter, and means for limiting the transient voltage surge which results due to the current-limiting feature of said circuit interrupter under severe fault conditions to a predetermined safe value comprising a circuit connected in parallel with said fusible element including a plurality of parallel gaps of different spacing which normally carry substantially no current until after fusion of said fusible element.

EDWIN A. WILLIAMS, JR.
